M. V. B. Darling,
Steam Cut-Off.
No 11,246. Patented July 11, 1854.

UNITED STATES PATENT OFFICE.

MARTIN V. B. DARLING, OF PROVIDENCE, RHODE ISLAND.

SLIDE-VALVE MOTION OF STEAM-ENGINES.

Specification of Letters Patent No. 11,246, dated July 11, 1854.

To all whom it may concern:

Be it known that I, MARTIN V. B. DARLING, of the city and county of Providence and State of Rhode Island, have invented a new and useful Improvement in Slide-Valve Motions of Steam-Engines, to make the valve cut off the steam at various points in the stroke as may be desired; and I do hereby declare that the following is a full, clear, and exact description of the same, reference being had to the accompanying drawings, forming part of this specification, in which—

Figure 1 is a longitudinal section of the cylinder and slide valve of an engine, with a side view of the valve motion. Fig. 2 is a top view of the same.

Similar letters of reference indicate corresponding parts in both figures.

My invention consists in a certain mode of combining together, and applying to the valve a cam and eccentric, the former for moving the valve to open the steam ports, and the latter to close them, whereby the ports are opened and closed with sufficient rapidity to enable the steam to be admitted full on the piston, and cut off at any point between about one fourth, or even less, of the stroke of the piston, and the end of said stroke.

To enable those skilled in the art to make and use my invention, I will proceed to describe its construction and operation.

A, is the steam cylinder, which is represented with a separate exhaust port for each steam port, and fitted with two valves, a, a, but this is not essential to my invention, as it is well understood that the operation of the single short slide is the same as that of the two valves, as represented.

b, is the way shaft, carrying the arm, c, to which the valve rod is attached, and the arm, d, with which connects the rod, e, from a yoke, f, f, which surrounds the cam, g, on the crank shaft, i. This cam is of such form, and so arranged upon the shaft, that it will give the proper length of stroke to the valve for opening first one, and then the other of the steam ports, and that it will open the ports wide very early in the stroke of the piston. It fits to the yoke in such a way, that very soon after it has passed the position at which it arrives to open the port wide, it will allow the yoke to receive such a movement independently of it, as would cause the valve to close the port. At the

side of the cam, g, is placed the eccentric, h, which is made capable of giving about twice the amount of motion given by the cam, g, in order that it may be capable of giving the valve a quicker motion than the cam. The eccentric rod, j, which receives the motion of the eccentric, has an eye, k, rigidly attached to its end, and this eye is of such size internally, as to be capable of sliding freely on the yoke rod, e, or of allowing the side rod to slide freely through it, and the yoke rod, e, is furnished with two fixed stops or tappet pieces, l, l', one on each side of the eye, k, to control the sliding motion of the eye and the rod, the one upon or within the other. The eccentric requires to be set in such relation to the crank, as the desired point of cutting off may require. If it be desired to cut off at half stroke, the eccentric is set one quarter of a revolution in rear of the crank; if at one quarter of the stroke, one eighth of a revolution; if at three quarters of the stroke, three eighths of a revolution and so on. The above rule applies only when the valve receives its motion directly from the shaft, but when a counter motion is used as represented, the eccentric requires to be in a position diametrically opposite to those described, as an illustration of which see the drawing where the steam is intended to be cut off just after half stroke, and the eccentric is set a little less than half a revolution in advance of the crank. The distance between the stops, l, l', on the yoke rod should be equal to the length of motion given by the eccentric, h, plus the depth of the eye, k, and the position of the stops on the yoke rod will depend upon the length of the eccentric rod, which may be about half that of the yoke rod.

The operation of the cam and eccentric on the valve can be best explained by reference to the drawing, where the direction of the revolution of the crank and the motion of the piston, are indicated by arrows, the cam has nearly arrived on its center and the steam port, n, is nearly wide open. The yoke rod is now moving in the direction of the arrow, 5, but the eccentric rod is moving in the opposite direction, as indicated by the arrow, O. As soon as the cam arrives on its center, the port will be full open, and will remain so as the cam continues its movement, owing to the shape of the cam not being such as to return the yoke rod at once. The eccentric, as it continues moving

in the same direction, will bring the eye, *k*, in contact with the stop, *l'*, and move the rod, *e*, along with it, until, by the time the eccentric is on its center, the valve has 5 moved back far enough to close the port, *n*. It will be understood, that a similar action takes place during the movement of the piston in the opposite direction, the eccentric always leaving the valve or valves in proper 10 position to be operated upon by the cam when it comes around.

I, by no means, confine myself to the employment of an eccentric to close the valve, as a cam would effect the desired result; 15 but I merely use the eccentric, for the reason that it works and wears more smoothly and evenly than a cam and yoke, and I only use the cam to open the valve for the sake of opening the port fully, very early in the 20 piston's stroke.

What I claim as my invention, and desire to secure by Letters Patent, is:—

1. Combining the cam and yoke motion for opening the steam port, and the eccentric or cam and yoke motion for closing the 25

steam port, and causing the two motions to act on the valve, by connecting with the valve the yoke rod, *e*, of the cam and yoke motion which gives the movement for opening the port, and furnishing the rod, *j*, of 30 the eccentric or cam motion which gives the movement for closing the valve, with an eye, *k*, or its equivalent, which plays between two stops or tappet pieces, *l*, *l'*, properly arranged on the rod, *e*, substantially 35 as described.

2. Giving to the eccentric, *h*, or cam, which gives the movement to close the valve a greater throw than the cam, which opens the valve, in order that, at the proper time, 40 the valve may be made to close the steam port and cut off the steam very quickly, or by a very small part of the revolution of the main shaft, as herein substantially set forth.

MARTIN V. B. DARLING.
